DESIGN FOR A LOCK

Samuel R. Fraim, Lancaster, Pa.

Application May 5, 1939, Serial No. 84,811

Term of patent 3½ years

To all whom it may concern:

Be it known that I, Samuel R. Fraim, a citizen of the United States, residing in School Lane Hills, Lancaster, Lancaster County, Pennsylvania, have invented a new, original, and ornamental Design for a Lock, of which the following is a specification, reference being had to the accompanying drawing, forming part thereof, in which:

Figure 1 is a front perspective view of a lock showing my new design;

Figure 2 is a rear perspective view thereof; and

Figure 3 is a bottom plan view.

I claim:

The ornamental design for a lock, substantially as shown.

SAMUEL R. FRAIM.
